(57) **CLAIM**

The ornamental design for a battery terminal as shown and described.

DESCRIPTION

FIG. 1 is a perspective view of the battery terminal;
FIG. 2 is a perspective bottom view thereof;

FIG. 3 is a top view thereof;

FIG. 4 is a bottom view thereof;

FIG. 5 is a front view thereof;

FIG. 6 is a rear view thereof;

FIG. 7 is a right side view thereof; and,

FIG. 8 is a left side view thereof.

The broken lines show portions of the battery terminal that form no part of the claimed design.
